[57] **CLAIM**

I claim the ornamental design for a pull, as shown and described.

DESCRIPTION

FIG. 1 is a perspective view of the pull according to a preferred embodiment.

FIG. 2 is a top plan view of the pull.

FIG. 3 is a front elevation view of the pull.

FIG. 4 is a side elevation view of the pull; and,
FIG. 5 is a bottom plan view of the pull.

The broken lines at the base of the stems and in the center of the bottom surface represent the bounds of the claim and all others are for illustrative purposes only. None of the broken lines form a part of the claimed design.
